METHOD FOR REMOVING WEAKLY ACIDIC
SUBSTANCES FROM SUBSTANTIALLY
NEUTRAL ORGANIC WATER-IMMISCIBLE
LIQUID

George W. Ayers, Jr., Chicago, and Lawrence M. Henderson, Winnetka, Ill., assignors to The Pure Oil Company, Chicago, Ill., a corporation of Ohio

No Drawing. Application June 22, 1940,
Serial No. 341,904

10 Claims. (Cl. 196—30)

This invention relates to a method of removing acidic bodies from water immiscible liquids. More particularly, the invention is directed to the problem of removing sulfur compounds from hydrocarbon oils.

Hydrocarbon oils, particularly light distillates resulting from cracking higher boiling fractions frequently contain mercaptans and other acidic sulfur compounds which require removal in order to render the oil "sweet" and non-corrosive. It has been common practice in the petroleum refining art to remove part of the sulfur compounds by washing with caustic alkali and then to sweeten with doctor solution. The disadvantage involved in this type of treatment is that a considerable portion of the sulfur remains in the oil or distillate and adversely affects the anti-knock properties of the gasoline. Gasoline containing sulfur compounds such as organic disulfides, not only has a lower octane rating than substantially sulfur-free gasoline, but requires much more tetra-ethyl lead to raise its octane rating to a given value.

More recently an improvement in caustic washing for removal of mercaptans and other sulfur compounds has been effected by adding to the caustic solution materials such as sodium or potassium isobutyrate, commonly known as "solutizers."

We have discovered that the results obtained by washing with caustic alkali solution either alone or containing commercially known solutizers can be considerably improved upon by adding to caustic alkali solution of fairly high concentration a soap or acid, the solubility of which in the alkali solution is low, and a solventizer therefor, i. e., a substance which will enable larger quantities of the soap or acid to dissolve in the caustic solution.

Caustic alkali solutions of fairly high concentration will dissolve only relatively small quantities of acid or soaps such as naphthenic acids and hydro-aromatic carboxylic acids and the soaps thereof, and in the quantities that the soap or acid is dissolved in the caustic alkali it has no

material effect insofar as enhancing the ability of the caustic solution to remove acidic substances such as mercaptans and thiophenols from hydrocarbon oils. However, if a material is added having the ability to increase the solubility of the soap or acid in the caustic alkali and a sufficient amount of soap or acid is added to the caustic solution, the ability of the caustic to remove mercaptans and other sulfur compounds is greatly enhanced.

On the other hand, caustic alkali solutions of low concentrations will dissolve relatively large amounts of naphthenic or other acids and their soaps, but in low concentrations the caustic alkali solution per se or with addition of the acid or soap is relatively ineffective in removing mercaptans from the oil. If an attempt is made to increase the concentration of the caustic to a point where it is fairly effective in removing mercaptans, the naphthenic acid or other acid soap precipitates out of solution.

Although a number of different compounds such as phenols and glycols such as phenol and ethylene glycol can be used as solventizers for the acids and soaps, we have found that those phenols having more than six carbon atoms in the molecule, such as p-, m-, xylenols, o-cresols and alpha-naphthol, and thiophenols such as thiophenol, m-thiocresol and o-thiocresol which per se have the ability to enhance the mercaptan removing ability of caustic solutions, give superior results. The solventizer must be soluble in the resulting solution to the extent of at least 2% by weight of the solution. In order to realize to an appreciable extent the benefits of the invention the solution should contain at least 5% by weight of free caustic alkali, either sodium or potassium hydroxide. The soap or acid is preferably added in amounts ranging from 10%, calculated in terms of equivalent acid, of the caustic solution up to an amount corresponding to the maximum amount of soap soluble in the caustic alkali solution. The amount of solventizer may vary with the particular solventizer and particular soap employed and may be as low

as 2% by weight of the caustic alkali solution. When using solventizers such as phenol, which have no substantial ability per se when added to caustic solution to enhance the mercaptan extracting ability of the caustic, the amount used should preferably not exceed that amount necessary to dissolve the desired amount of soap in the caustic. But in the case of certain solventizers such as the thiophenols, which in themselves have the ability to enhance the mercaptan extracting ability of caustic solutions, the amounts used may range from the minimum required to dissolve the desired amount of soap up to the maximum amount soluble in the caustic solution. The combinations of the thiophenols and soaps in caustic alkali solution of suitable concentration are even more effective than solutions in which a solventizer is used which in itself is not an effective reagent for removing mercaptans.

The acids and soaps which have been found to be particularly effective are the naphthenic acids and their soaps. These soaps, as well as others, are preferably added to the caustic solution as the sodium or potassium soap or as the acid per se. When acid is added instead of soap, the soap forms in situ.

A large number of tests were carried out using three commercial samples of naphthenic acid recovered from mineral oils, having the following properties:

¹ Cracking.

An attempt was made to prepare an aqueous solution of 40% of naphthenic acids in caustic soda solution of such concentration of caustic that the resulting solution would contain 14.6% of free sodium hydroxide as determined by titration to phenolphthalein end point, using each of the three naphthenic acids above mentioned. A large part of the naphthenic acid salt precipitated out of solution as the sodium salt so that in no case did the resulting solution contain as high as 8% of sodium naphthenate calculated as naphthenic acid. The same experience was encountered in an attempt to prepare caustic potash solutions. On the other hand, when a small amount of phenol or m-cresol or corresponding thio compound was added to the caustic alkali solution, a solution containing 20% to 25% of naphthenate calculated as naphthenic acid was prepared with great ease.

The following table gives the results obtained by treating gasoline prepared by high pressure thermal cracking of a mixture of oil from Van Zandt and Schuler crudes. In the following table, "free NaOH" and "free KOH" represent NaOH or KOH present in the solution, determined by titration to a phenolphthalein end point.

Table II

5	Sample No.	Treating agent (aqueous solutions)	Mercaptan sulfur in gasoline before treatment	Mercaptan sulfur in gasoline after one wash with 10% of treating solution	Mercaptan sulfur removed
10	1	Caustic soda solution containing 0.77% by weight of NaOH	Percent 0.0233	Percent 0.0168	Percent 28
	2	Caustic soda solution containing 0.77% free NaOH, 25% naphthenic acid, sample #3 (as sodium salt)	0.0233	0.0186	20
15	3	Caustic soda solution containing 14.6% by weight of NaOH	0.0267	0.0116	57
	4	Caustic soda solution containing 14.6% by weight free NaOH, 26% by weight phenol	0.0252	0.0106	58
20	5	Caustic soda solution containing 14.6% by weight free NaOH, 38.7% by weight phenol	0.0252	0.0220	13
	6	Caustic soda solution containing 14.6% by weight free NaOH, 8.4% by weight phenol, 25% by weight naphthenic acid (1) (as sodium salt)	0.0267	0.0051	81
25	7	Caustic soda solution containing 14.6% by weight free NaOH, 8.4% by weight phenol, 25% by weight naphthenic acid (2) (as sodium salt)	0.0237	0.0048	82
	8	Caustic soda solution containing 14.6% by weight free NaOH, 8.3% by weight phenol, 25% by weight naphthenic acid (3) (as sodium salt)	0.0267	0.0044	84
30	9	Caustic soda solution containing 14.6% by weight free NaOH, 13.0% by weight naphthenic acid (1), 12.0% by weight phenol	0.0252	0.0087	73
	10	Caustic soda solution containing 14.6% by weight free NaOH, 2.9% by weight phenol, 20.3% by weight naphthenic acid (1)	0.0252	0.0058	77
40	11	Caustic potash solution containing 20.5% by weight KOH	0.0262	0.0106	60
	12	Caustic potash solution containing 20.5% by weight free KOH, 8.3% by weight phenol, 25% by weight naphthenic acid (1) (as potassium salt)	0.0262	0.0009	97
50	13	Caustic soda solution containing 14.6% by weight free NaOH, 8.3% by weight m-cresol, 25% by weight naphthenic acid (1) (as sodium salt)	0.0262	0.0027	90

¹ Gasoline only slightly doctor sour.

55 Sample #12 was given a second treatment with 10% by volume of fresh treating solution followed by two 10% by volume water washes. The mercaptan sulfur after the second wash was only 0.0002% and the gasoline was sweet to the doctor test.

60 In each of the foregoing tests the gasoline was shaken with the treating solution for a period of fifteen minutes and then washed with two 10% by volume water washes.

65 The foregoing results clearly show that the dilute caustic alkali either alone or in which has been dissolved only naphthenic acid is relatively ineffective to remove mercaptan sulfur from cracked gasoline and that the effectiveness of caustic alkali solution of 14.6% NaOH was greater than that of the 0.77% caustic solution. Furthermore, caustic potash used in conjunction with the naphthenic acid soaps and solventizer is more effective than caustic soda. They also show the phenol not only does not enhance the mercaptan

removing ability of caustic soda, but when added in too large amounts actually detracts from the ability of caustic soda to remove mercaptans and therefore should not be added in larger amounts than necessary. The results further show that with increasing amounts of naphthenic acids in more concentrated caustic alkali solution the ability of the solution to remove mercaptans increases.

In order to determine the efficacy of the thiophenols in combination with soaps such as those of naphthenic acids in caustic solution a reagent was made by dissolving 20% of naphthenic acid (1) together with 6.7% o-thiocresol in a caustic soda solution, the free NaOH concentration of which was 14.6% by weight after addition of the naphthenic acid and thiocresol. This solution sweetened a sample of cracked gasoline containing 0.0213% mercaptan sulfur prepared from a mixture of Van Zandt and Schuler crudes with one 10% by volume treatment. When the same gasoline was treated with the same volume of a 14.6% caustic soda solution, only 57% of the mercaptan sulfur present in the gasoline was removed and the gasoline was distinctly sour.

Another reagent was prepared by dissolving 10% of o-thiocresol, 10% of m-cresol, and 20% of naphthenic acid (1) in caustic soda solution containing 14.6% free NaOH, and Stoddard solvent, containing 0.0372% of mercaptan sulfur, fractionated from Illinois crude, was treated with the solution. The mercaptan sulfur was lowered to .001% whereas the treatment of the same Stoddard solvent with straight caustic soda solution containing 14.6% caustic soda removed only 8% of the mercaptan sulfur present. Thus it will be seen that naphthenic acids or soaps thereof when used with solventizers such as the thiophenols which are in themselves effective agents in caustic solution for removing mercaptans have a much greater ability to remove mercaptans than naphthenic acids in the presence of solventizers which of themselves have little or no effect on mercaptan removal.

When using solventizers of the type which are in themselves effective to enhance mercaptan removal by caustic alkali, it is preferred to use quantities ranging from 5% to 40% by weight of the solution.

It will be apparent that in preparing treating reagents in accordance with the invention, the solventizer may be added as the alkali compound and the soap may be added as such or the acidic components may be added to the alkali solutions and the soap and alkali solventizer compounds formed in situ.

The specific examples given are only by way of illustration and are not intended to limit the invention to the specific quantities given or the particular compounds named. Mixtures of the various solventizers may be used as well as mixtures of different soaps. It is important, however, that sufficient quantities of free alkali, solventizer and soap be present to obtain the full benefits of the invention.

Although we have found that solutions containing from 5% of free caustic alkali up to the maximum amount soluble in the solution may be

used, we prefer to use solutions containing from approximately 10-20% of free sodium hydroxide or 10-40% free potassium hydroxide. The invention also contemplates the use of alcoholic alkali as well as aqueous alkali solutions.

Treating solutions in accordance with this invention can be regenerated in the same manner as caustic alkali solutions, namely, by boiling or by steam stripping, and reused either with or without adjusting the alkali concentration of the solution, and with or without further additions of naphthenic acids and/or phenols.

We claim:

1. In a method for removing weakly acidic substances from substantially neutral organic water-immiscible liquids, the step which comprises contacting said liquids with an aqueous caustic alkali solution containing at least 10% by weight of free caustic alkali, an amount of alkali metal soap of naphthenic acid substantially in excess of that amount soluble in the caustic alkali solution in the absence of a solventizer and sufficient to materially enhance the ability of the caustic alkali solution to extract said acidic substances from substantially neutral organic water-immiscible liquids and a sufficient amount of solventizer to dissolve the soap.
2. The step in accordance with claim 1 in which the solventizer is a glycol.
3. The step in accordance with claim 1 in which the solventizer is ethylene glycol.
4. In a method for removing mercaptans from hydrocarbon liquids, the step which comprises contacting said fluids with an aqueous solution containing at least 10% by weight of free caustic alkali, at least 10% by weight alkali metal soap of naphthenic acid calculated as acid, and a sufficient amount of solventizer to dissolve the soap.
5. The step in accordance with claim 4 in which the caustic alkali is sodium hydroxide.
6. The step in accordance with claim 4 in which the solventizer is a glycol.
7. The step in accordance with claim 4 in which the solventizer is ethylene glycol.
8. In a method for removing weakly acidic sulfur compounds from hydrocarbon oils, the step which comprises contacting said oils with aqueous alkali metal hydroxide solution containing at least 10% by weight of free alkali metal hydroxide, at least 10% by weight of alkali metal soap of naphthenic acid calculated as acid, said acid having a boiling range of not less than about 475° F. at 10%, to 610° F. at 90% and at least 2% by weight of solventizer.
9. The step in accordance with claim 8 in which the alkali metal hydroxide is sodium hydroxide and the amount of free sodium hydroxide is between approximately 10% and 20% by weight.
10. The step in accordance with claim 8 in which the alkali metal hydroxide is potassium hydroxide and the amount of free potassium hydroxide is between approximately 10% and 40% by weight.
